UNITED STATES PATENT OFFICE.

JOHN H. B. REA, OF LA FAYETTE, GEORGIA.

RAILWAY TIE.

Application filed August 27, 1923, Serial No. 659,629. Renewed July 3, 1924.

To all whom it may concern:

Be it known that I, JOHN H. B. REA, a citizen of United States, residing at La Fayette, in the county of Walker and State of Georgia, have invented certain new and useful Improvements in Railway Ties; and I do declare the following to be a full, clear, and exact description of the invention, such as will enable others skilled in the art to which it appertains to make and use the same.

My invention relates to improvements in railway ties of the type employing a metal shell filled with cement, one object being 15 to provide a rather simple and inexpensive, yet an exceptionally rigid and durable tie provided with a unique form of internal reinforcement and brace.

Another object is to construct a novel 20 form of rail chair which also ties together, two longitudinal channel metal beams, of which one form of the shell is formed.

My invention also relates to ties adapted 25 for use on bridges and trestles, a further object being to provide a novel means on the lower side of the tie to engage the inner sides of the tie supporting stringers, thus holding the tie against shifting thereon, provision being made whereby the same 30 bolts may be used for holding the stringer-engaging means and a pair of guard rails in place.

With the foregoing in view, the invention resides in the novel subject matter 35 hereinafter described and explained, the description being supplemented by the accompanying drawings.

Figure 1 is a top plan view of one form 40 of my invention.

Figure 2 is a side elevation.

Figure 3 is a longitudinal sectional view 45 as indicated by line 3-3 of Fig. 1.

Figure 4 is a vertical transverse section on line 4-4 of Fig. 3.

Figures 5, 6, 7 and 8 are duplicates of 50 Figs. 1, 2, 3 and 4, with the exception that they illustrate a different form of construction.

In the form of construction shown in 55 Figs. 1, 2, 3 and 4, the numerals 1 designate a pair of spaced, parallel channel beams, having their flanges extending inwardly toward each other. At the upper side of the tie, these flanges are tied together by a pair of end plates 2 and a central plate 3, the latter being riveted at both

ends to the beams 1, as indicated at 4. Obliquely opposite corners of the plates 2 are secured to beams 1 by rivets 5, while bolts 6 preferably pass through the other 60 corners of said plates 2 and are provided with large washers 7 which are adapted to overlie the bases of the line rails 8.

At the lower side of the tie 1, a pair of transverse end plates 9 and a central transverse plate 10 are riveted to the beams 1, the latter and plates 2, 3, 9 and 10, forming a hollow metal shell adapted to be filled with concrete or cement as indicated at 11. As disclosed at 11^a the cement at the ends 70 of the tie, may extend upwardly between the beams 1 and abut the outer edges of the plates 2. Both the outer and inner portions of these plates, are preferably bent over upon themselves as indicated in 12, 75 to provide a pair of shoulders between which the base of the rail 8 is snugly received, to hold said rail against lateral shifting.

To generally brace and reinforce the tie, 80 I provide a longitudinal bar 13 whose center is rigidly secured by a bolt or the like 14 to the transverse plate 3, the end portions of said bar being extended obliquely to the end plates 9 and having their extremities bent to provide hooks 15 which hook over the outer edges of the last-named plates. In addition to this securing means, rivets 15^a may well secure the bar ends of 85 end plates 9.

To permit insertion of new bolts, in case the bolts 6 should be broken, I prefer to form openings 16 in the beams 1, the cement filler 11, being provided with recesses 17 which communicate with said openings and 90 receive the bolt heads.

In Figs. 5, 6, 7 and 8, a one-piece hollow shell 1^a is provided, filled with cement of the like 11^a. To secure the rails 8^a upon this form of tie, I have shown four bolts 6^a 100 and washers 7^a, for each rail, said bolts being passed through the top of the shell 1^a and through metal plates 12^a secured by rivets or the like 5^a, to said top, thus holding the rail against lateral shifting. Each vertical side of the shell 1^a is formed with openings 16^a and the cement filler 11^a is formed with recesses 17^a, permitting old bolts 6^a to be removed and others to be inserted. 105

Within the shell and embedded in the cement filler 11^a, is a longitudinal bar 13^a 110

whose center is secured by bolts or the like 14^a to the top of said shell; the ends of said bar being formed with hooks 15^b, which hook over the ends of the shell bottom.

5 In connection with both forms of my invention, either of which may be used on bridges or trestles, I have shown a longitudinal bar 18 secured against the lower side of the shell by vertical bolts 19, the ends of 10 said bar being bent downwardly as indicated at 20 to abut the inner sides of the usual tie-supporting stringers 21, thus holding the tie against endwise movement. The 15 upper ends of the bolts 19 project above the tie and serve as means for securing suitable guard rails 22 in place.

As excellent results may be obtained from the general construction disclosed, such construction may be followed if desired, but 20 within the scope of the invention as claimed, numerous minor changes may be made.

I claim:

1. A railway tie comprising a concrete body member, a metal shell disposed around 25 said body member, and a metal reinforcing bar disposed in said body member and extending longitudinally therethrough, said bar being secured at its center to one side of said shell and having its ends secured 30 to the end portions of the opposite side of said shell:
2. A railway tie comprising a concrete body member, a metallic shell disposed around said body member; and a metal re- 35 inforcing bar embedded in said body mem-

ber and extending longitudinally therethrough; the intermediate portion of said bar being secured to one side of said shell and the ends of said bar being bent to form hooks which are hooked around the end portions 40 of the opposite side of said shell.

3. A railway tie comprising a pair of parallel channel beams having their channels disposed inwardly toward each other, transverse plates secured to the centers and ends 45 of said beams, and a longitudinal metal-reinforcing bar between said beams, said bar being secured at its center to one of said transverse plates at one side of the tie and having its ends secured to other of said 50 plates at the opposite side of the tie.

4. A railway tie comprising a pair of spaced parallel beams, transverse rail supporting plates secured to the upper sides of 55 said beams and having their side edges bent upon themselves to engage the edges of the rail bases, and means for securing the rails to said plates.

5. The combination with a railway tie adapted for use on bridges and trestles having tie-supporting sills of a longitudinal bar 60 against the lower side of said tie having downturned ends to abut the sills, and bolts passing through said bar and tie to secure them together; said bolts extending above 65 the tie to secure guard rails in place.

In testimony whereof I have hereunto affixed my signature.

JOHN H. B. REA.
